CLAIM

The ornamental design for a golf collectible, as shown and described.

DESCRIPTION

FIG. 1 is a front elevational view of a golf collectible showing my new design;

FIG. 2 is a right side elevational view with the left side being a mirror image thereof;

FIG. 3 is a bottom view thereof; and,

FIG. 4 is a rear elevational view thereof.

The broken line showing of an autograph in FIG. 1 is for demonstrative purposes only and forms no part of the claimed design.
